UNITED STATES PATENT OFFICE.

MAXIMILIAN C. MEYER, OF BROOKLYN, NEW YORK.

CARD GAME.

Application filed December 5, 1925. Serial No. 73,297.

This invention relates to a card game, and more particularly to the game of base ball played by means of suitable playing cards, adequate in number to execute the majority 5 of the major plays of base ball.

One object of the invention is to provide a new and fascinating card game that requires skill to win, the element of chance being reduced to a small percentage.

10 A further object of the invention is to provide a game of playing cards adequate in amount for convenient manipulation and for economical production.

15 A further object is to provide a game to be played with cards, according to the standard rules of base ball.

20 A further object is to provide playing cards having such indications or directions thereon as, under suitable rules of play, will enable the game of base ball to be followed according to the standard rules of that sport.

Other objects of the invention will appear more fully hereinafter.

25 The invention consists in the provision of a plurality or a deck or pack of playing cards having thereon indications, designs, marks or directions of such nature as to enable two or more persons to play such 30 cards according to guiding rules based on the standard rules of the base ball game governing the different plays and situations encountered in and to score the results, as in a real base ball game.

35 Referring to the drawings:

Figs. 1 to 27 show, respectively, different playing cards included in the deck, embodying the principles of my invention.

40 The disclosed game uses 27 cards for a deck, but I do not wish to be limited in this respect except as required by the claims, since it is possible to use a greater or less number of cards when desired.

45 I will describe the cards, and the various indications, designs, marks or directions contained thereon, in connection with general rules for guiding the players in the use thereof, and in executing different plays, and in scoring the results, all as embodied 50 in my invention.

55 While the cards of my deck do not fall into what are known in the art as suits, it is possible to group them in several ways depending upon the particular indicia used as a basis for the grouping. Thus, using

the center picture of the card in Fig. 1 as a basis, there are twelve cards with this picture thereon. Using that in Fig. 3 as a basis, there are twelve cards in the group, and using that in Fig. 4, there are three in 60 the group. Twelve of the cards are marked in the corner with the word "Fast," seven with the word "In" and eight with the word "Out."

There is one card Fig. 9, showing a hit 65 pitcher, three cards Figs. 25, 26 and 27, showing the double play marking and the manner played. Thus, in Fig. 27, the play is from second base to first base, in Fig. 26 from short stop to third base, and then to 70 second base. In Fig. 25, the play is from third base, to home plate, and then to first base.

In Figs. 1 to 8, the circle with the square in the center represents a single to right 75 field (RF) or to left field (LF). The circle with the two white hemispheres in Figs. 10 to 12, indicate a two base hit either to right field (RF) or to left field (LF). Those with three white segments, Figs. 19 and 20, 80 indicate a three base hit to left center field (LCF) or to right center field (RCF). The circle with the four white segments, Fig. 21, indicates a home run to deep center field (DCF). 85

In Figs. 13 to 18, the illustration at the side of the card indicates a throw out to first base by either the catcher (C), third baseman (TB), second baseman (SB), first baseman (FB), short stop (SS), or pitcher 90 (P). In Figs. 22, 23, and 24 there is shown at the side of the card an indication representing that the batter flied out to center field (CF), left field (LF) or right field (RF). 95

Two or more persons can play the game, and a game is regarded as being completed at the end of nine "innings."

When more than two persons desire to play teams may be chosen, one member of 100 each team being termed the captain.

A member of each or either team may act or play for one or more members of the team, or, if desired, the members of each team may act or play successively in regular 105 "batting order."

In the preparation for playing the game, the cards are shuffled or mixed and then spread out, face downward. Each player, if only two are playing, or a member or the 110

captain of each team if opposing teams are playing, draws a card. The player member or captain of a team drawing a card having thereon a previously selected indication or 5 feature, such, for example, as a red ball, is supposed to take the field, while the other player or team is supposed to be "in" or "batters." The drawing of cards is repeated if both cards drawn contain the same 10 preselected indication.

Having thus determined who and which team will take the field, the player or member of that team who is to represent the "pitcher" mixes or shuffles the cards. The 15 opponent or the member of the opposing team who is to represent the first "batter" up, then cuts the deck. The "pitcher" proceeds to deal the cards, one to his opponent and then one to himself, and so on, until a 20 desired number, usually six cards, are dealt to each. The remaining cards of the deck are placed face down in the center of the table.

The game is now inaugurated by the 25 "pitcher" and the "batter" each selecting and playing a card from his own hands. This is effected in two distinct motions or operations. In the first motion, each player selects from his hand the particular card 30 he chooses to play, and holds the selected card with its face concealed from the opposing player. Usually this motion is effected by each player holding his selected card up or in front of him with its face towards 35 himself. In the second motion, the two selected cards are placed simultaneously on the table between the players, the "pitcher's" card at all times being placed with face up, and the "batter's" card being placed either 40 with its face up or with its face down according to the choice of the "batter". The play of the "pitcher's" card signifies that a "ball" is "served" or pitched to the "batter". The play of "batter's" card with its 45 face up signifies that the "batter" attempts to strike at or connect with the "pitched" or "served" ball. The play of the "batter's" card face down signifies that the "batter" proposes to let the "pitched" or "served" 50 ball pass without attempting to strike at it or connect with it.

The character of the pitched ball "pitched" 55 or served by the pitcher, that is, whether it is an inshoot or an outshoot, or a straight fast ball, is determined by designs, pictures, words, letters or other representations, printed or otherwise, produced on the faces of the cards, and, for this purpose, groups 60 of cards of the deck are provided with suitable indications or markings. These indications or markings may be of any desired nature or character. For illustration of one form in which this may be carried out, although it is to be understood that my invention is not to be limited in this respect,

the cards in one group may have the word "In" printed thereon, or a pictorial representation of a base ball, as indicated at 11 in Fig. 8, to signify a pitched ball "pitched" or "served" by the "pitcher" with an "in-shoot" or an "incurve", when the "pitcher" selects and plays a card of this group. The play of a card of this group by the "pitcher" is recorded as a safe hit, a sacrifice hit, an out, a "strike", or a "ball" according to the 15 card played by the "batter", or whether the "batter", in playing his card, does so in a manner, as above explained, to signify his intention to hit at the "pitched" ball, or to let the "pitched" ball pass without attempting to strike at it. If the "batter" plays his card face up, and its designation or printed design, picture, feature or the like matches that of the card played by the "pitcher", that signifies that the batter attempted to 20 "connect" with the pitched ball and succeeded, resulting in a safe hit, a sacrifice hit, or an out. If the card played by the "batter" face up fails to match with the card 25 played by the "pitcher", that would indicate that the "batter" struck at the "pitched" or "served" ball and failed to "connect", and a "strike" is recorded. In case the "batter" plays his card face down, thereby 30 signifying his intention to let the "pitched" or "served" ball pass without attempting to "strike" at or "connect" with it, and the "pitched" ball is an inshoot or incurve, as indicated on the face of the card 35 played by the pitcher, then the play is 40 recorded as a "ball".

In like manner the cards of another group may be marked, printed, or otherwise constructed, to signify an "outshoot" 45 or "outcurve" when played by the "pitcher", and such a play is recorded likewise as a safe hit, a sacrifice hit, an out, a "strike" or a "ball", according to the play, and the card played by the "batter" in the same way, as 50 above explained with reference to the "in-shoot" or "incurve". And as one illustrative form of this designation, marking a feature in this group of cards, the word "out" is 55 printed thereon, or on a pictorial representation of a ball, as shown at 7 in Fig. 4.

Similarly, the cards of another group are 60 printed, marked or otherwise constructed to signify that a fast straight ball is "pitched" or "served" when such a card is played by the pitcher; that is, the ball that passes over the "plate" within the range of height constituting a strike according to the standard base ball rules. For illustrative purposes the word "Fast" is shown printed on the card or on the pictorial representation of the base ball, as indicated at 1 in Fig. 1. When a card of this group is selected and played by the pitcher, it is recorded as a 65 safe "hit" or otherwise, according to the play, and the card played by the "batter".

If the "batter" plays his card face down, a "strike" is scored against him. If he plays a card face up which fails to match the card played by the "pitcher" it likewise is recorded as a "strike", and if he plays a card face up which matches that played by the "pitcher" it signifies he connected with the pitched ball, resulting in either a safe hit, a sacrifice hit, or an out.

If desired, and in order to more readily distinguish the cards of these respective groups, the indications, 11, 7 and 1, whatever be the form or nature thereof, may be of relatively different colors. For example, the indications 11 may all be yellow, 7 may be blue, and 1 red. My invention, however, is not to be restricted in this respect.

As above indicated, when the "pitcher" plays a card from one or another of the groups referred to, from his hand, it indicates that he "pitches" or "serves" to the "batter" a "pitched" ball of the character indicated on the card so selected and played.

And when the "batter" simultaneously plays a card from his hand, but plays it face down, that indicates that the "batter" makes no attempt to "hit" or "connect" with the "pitched" ball, with the result as above explained, of scoring a "strike" or a "ball" according to the nature of the card played by the "pitcher". On the other hand, when the card is played by the "batter" face up, and it matches with the card played by the "pitcher" with respect to the nature of the "pitched" or "served" ball as printed, marked or otherwise produced thereon, such a play signifies that the "batter" "connects" with or succeeds in "hitting" the "pitched" or "served" ball, and scores a "hit" either "safe" or otherwise, as will be hereinafter more fully explained. If the card played by the "batter" face up fails to match with that played by the "pitcher" in the manner described, such play signifies that the "batter" struck at the "pitched" or "served" ball but missed it, thereby scoring a "strike".

Having now explained the card game of my invention with special reference to one of the major phases of the game of base ball, namely, that phase which particularly concerns the "pitcher" and the "batter", I will now describe the other features of the card game with reference to other major phases of the game of base ball, particularly the phases of such game which concern the results of the "hits" scored by the batter, whether they be safe hits, or otherwise, and the resulting "fielding" or "base running" operations. It being understood, of course, that in scoring the plays with the cards the standard rules of the base ball game are to be observed. For instance, three "strikes" made and recorded against a "bat-

ter" puts him out, and four "balls" recorded allows the "batter" to take "first base", and a "base runner" already on first base to go to "second base", and so on. When one player of a team "nine" or "side" "strikes out" or is given a "base" on "balls", another player or member of the "team" "nine" or "side" takes his place as "batter". And when three men on a "team" "nine" or "side" is put "out" by "strikes", or by proper "fielding" or in "base running", as will be explained hereinafter, the "side" or "team" retires and exchanges places at the table or in dealing the cards, that is, the "pitcher" becomes the "batter" or the reverse, or a member of the "team" which before were "batters" or on the offensive, become the "pitcher" or play the defensive part of the game, and a member of the opposing team becomes the batter, all in strict accord with the standard rules of base ball.

Each card, except the one illustrated in Fig. 9 of the deck, in accordance with my invention, contains a suitable indication of one or another possible results of the "batter" "connecting" with a pitched ball. This indication may be printed, marked or otherwise produced or illustrated on the various cards, and may be of any desired or suitable form or design. Thus, for illustrative purposes, a rectangle inscribed within a circle, as indicated at 2, 4 and 5, Figs. 1, 2 and 3, respectively, represents a one-base hit, a circle divided into two parts, as indicated, for example, at 13, Fig. 10, represents a two base hit, a circle divided into three parts, as indicated at 22, 23, Figs. 19 and 20, respectively, represents a three-base hit; a circle divided into four parts, as indicated at 24, Fig. 21, represents a home run, or a four-base hit.

The one exception above noted, to the indication of the result of the pitched ball, occurs when the batter is struck by the pitched ball, permitting the hit batter to a free base. This result may be likewise indicated by an appropriate design, figure, lettering or otherwise. For illustrative purposes, I have shown at 12, Fig. 9 a pictorial illustration of a "batter" in the path of the pitched ball. Of course it is to be understood that any other suitable or appropriate illustration, lettering or design conveying, suggesting or indicating the idea that the "batter" is struck by the "pitched" or "served" ball may be used for this purpose.

In order to avoid unnecessary complications and delays in the playing of the game according to my invention, I have eliminated any cards carrying indications of "foul" balls and "fielding" "errors". These eliminations, however, do not detract substantially from the interest of the game.

The placing of the "hit" ball, that is, the

territory within which the "hit" ball lands, may, likewise, be indicated on the various cards containing the indicia, regarding the character of the "hit", and may be of any suitable or desired form, design, lettering, or the like. Thus the printed letters RF may be used to designate "right field"; CF center field, LF left field, LCF left center field, RCF right center field, and DCF deep center field. When one or another of these designations, or others employed for the same purpose, appears on a card played by the "pitcher", and the card played by the "batter" scores a "hit", the designations on the "pitcher's" card determine the nature and character of the hit, that is, whether a "one base", "two base", "three base" "home run" "hit", and whether to "right field", "center field", "left field", and so on. Thus, the character, design, illustration, or the like, shown, for example, at 2 in Fig. 1, indicates a single to right field, that of 4 in Fig. 2 indicates a single to center field, and that at 5 in Fig. 3 a single to left field. In like manner, the illustrative indications 13, 14 and 15, in Figs. 10, 11 and 12, signify respectively, "two base hits" or a "double", to "right field"; to "center field" and to "left field"; illustrative indications 22 and 23, in Figs. 19 and 20, signify respectively, a "three base hit" or "three bagger" to "left center field" and to "right center field"; and 24, Fig. 21, signifies a "home run" to "deep center field". These illustrative indications signify the results of "safe" hits, and the instances given are merely illustrative of the principles involved, it being understood that other possible "safe" hits may likewise be provided for by means of suitable indicia or other cards of the deck. So, too, where the "hit" is not effective to enable the "batter" to reach "first base" cards of the deck are provided with indicia of appropriate character or signification. Thus, one or another of the illustrative examples shown at 16, 17, 18, 19, 20 and 21, in Figs. 13, 14, 15, 16, 17 and 18 respectively, appears on the card played by the "pitcher" and when the "batter" plays the proper card face up to record a "hit", as hereinbefore explained, the recorded result of the "hit" is a "grounder" to either the "catcher", "third baseman", "second baseman", "first baseman", "short stop", or "pitcher", respectively, who throws the batter out at first base. And the illustrative indications 25, 26, 27, Figs. 23, 24, 25 respectively, signify that the "batter" hit a "fly ball" that was caught out by the "left fielder", the "center fielder" or the "right fielder", respectively.

In like manner, other possible fielding and base running plays may be indicated in suitable form on still other cards of the deck and the corresponding scores recorded in

accordance with standard base ball practice. Thus reference numeral 29, Fig. 26, designates an illustrative form of indication signifying a fast ground ball hit by the "batter" to the "second baseman", who, by tossing the ball to the "short stop", guarding "second base", forced "out" the runner from "first base", the "short stop", in turn, effecting a quick throw to "first base" putting the "batter" out, thereby completing a "double" play.

Reference numeral 30 in Fig. 27, indicates an illustrative example of a similar "double play" in which the "batter" hits to "short stop", whose throw to "third base" forces "out" the "runner" from "second base", and then the "third baseman" snaps the ball to "second base", thereby throwing out the "runner" from "first base". In Fig. 25 the illustrative indication 28, signifies a "double play" when the "bases" are "full". In this instance, the "batter" hits a fast "grounder" to "third baseman", whose throw to "home plate" forces "out" the runner from "third base"; the "catcher", in turn, whipping the ball to "first base", putting out the "batter".

In case the conditions are such that a "double" play, signified by the "pitcher's" card cannot be made effective, then the indication appearing on the card played by the "batter" will determine the play.

It will be quite obvious that other cards may be included in the deck in accordance with my invention containing indications representing other possible fielding plays encountered in playing a game of base ball, but the instances above given are illustrative of the principles involved.

Of course, it is to be understood that in the various example of base running and fielding plays hereinbefore mentioned, there should be the appropriate "base runners" on the various "bases" involved, in order to make the various plays effective. It is also to be understood that "base running", safe "hits", "runs", "flies", "outs", and the like, as well as the "batting" and "pitching" plays are to be scored in accord with the standard rules of the base ball game. Likewise, the rules of the base ball game with regard to a base runner advancing where a "batter" is caught out at "first base", are to be observed.

In carrying out my invention, I also propose to provide a way to permit the "pitcher" the privileges of making one attempt to catch a "base runner" "off base" before he "delivers" or "serves" each ball to the "batter". In playing the card game this result is accomplished by the "pitcher" first declaring aloud which base runner he will try to catch off base. After so declaring, the "pitcher" then draws a card from the pack or that portion of the deck which, ini-

tially is placed face down on the table. The attempt of the "pitcher" is successful or unsuccessful according to the character of indication appearing on the card which he so 5 draws from the pack or deck. For this purpose certain cards are provided with an appropriate marking or indication, by letters, words, illustrations or otherwise, to signify whether the "runner" is caught off 10 base or not. For example, and by way of illustration, if the "pitcher" draws a card containing a group picture, or other suitable marking, such as indicated at 9 in Fig. 4, or at 6 in Fig. 3, the "base runner" is caught 15 off base. But if the pitcher draws a card containing a group picture or other suitable marking, such as is indicated at 3, Fig. 1, the "base runner" is not caught off base.

I also propose to provide means whereby 20 "base stealing" may be attempted, in playing the card game of my invention, with results, as to success or failure, and scoring in accord with the standard rules of base ball. In case an attempt is to be made by a runner 25 or runners to steal bases, this play can be attempted only when the "pitcher" "serves" a ball to the plate, and the "batter" must declare which "base runner" or "runners" will make the attempt. This declaration 30 must be made after the first motion of the "pitcher" in playing a card, and before the second motion of the play is executed. In case the batter connects with the pitched ball after making the declaration referred 35 to, for a base hit, or a single or better, the base runner on first base and all the runners ahead of him will score a run, on this hit and run play. Should the "batter" fail to connect with the pitched ball after making the 40 declaration with reference to runners who will attempt to steal, then the "catcher" throws the ball to the base the runner is attempting to steal and relayed to other basemen to execute the required play. The 45 result of this play is indicated by appropriate markings on the top card of the deck or pack or portion thereof initially placed on the table. This top card is drawn by the 50 "batter" or by the captain or other member of his team.

An indication of the type or nature of that shown at 6, Fig. 3, or 3 of Fig. 1, will 55 determine the result of any or all runners attempting to steal. Should the top card of the deck or pack contain an illustration of indication of a different nature or type, then the succeeding cards of the deck or pack are to be drawn until a card is drawn with one 60 or other illustrations or indications of the character or type of 6 or 3, appearing thereon. This card, so drawn, will determine the results of the play. In like manner, a base runner or runners are privileged to attempt 65 to advance one base after a fly ball is caught. This play, in accordance with a card game

embodiment of my invention is executed and determined in the same manner as that above described in connection with base runners attempting to steal bases. In case the "batter" or the captain or other member of the 70 team decides to refrain from attempting to advance a base runner or runners after a fly is caught, then the fielder who caught the ball is permitted to attempt to catch the base runner off the base nearest the home plate. 75 This play is executed in the same manner as in the case of an attempt at stealing a base or advancing a base after a fly is caught, and is determined, as to result, by the character or type of illustration or marking of the 80 card drawn from the pack or deck. I have shown at 9; Fig. 4, an illustration or marking such as will signify the success of the fielder in catching the runner off base. If a card having some other illustration or type 85 is drawn, that will signify that the runner is safe.

From the foregoing description it will be seen that by providing suitable indicia on the cards, which indicia may take any desired form and be applied to the cards in any desired manner, a deck or pack of playing cards is produced by means of which the plays and situations arising in playing a regular game of base ball according to the 90 standard rules may be played with the cards.

And it is obvious that by providing each card of the deck or pack with indicia indicating or representing the three major 100 phases of action in playing base ball, namely, the phases of (a) pitching and batting (b) base running and (c) fielding, the deck or pack lends itself admirably to the working out of the various plays and situations encountered in the standard game, or to the working out of rules, general or special, by which such plays and situations may be simulated in playing the card game, thereby 105 adding interest and entertainment in the use of the cards.

It is obvious that provision may be made in the rules for penalties of various kinds; special rules for each nine inning game played with the cards may be adopted; standard or any desired score cards or forms 110 may be adapted and used and so on.

While I have shown and described a deck or pack containing twenty seven cards, my invention in its broadest scope, as defined in the claims, is not to be limited in this 120 respect.

Having now set forth the object and nature of my invention, and having shown and described a card game embodying the principles thereof, what I claim as new and useful and of my own invention, and desire to secure by Letters Patent is:

1. A base ball card game comprising a plurality of cards having indicia thereon 125 by means of which base ball plays may be 130

simulated including pitched balls, base hits, base running, and double plays, each card having at least three of these indications, and each card having a design thereon to indicate which play is effective.

2. A base ball card game comprising a deck of twenty-seven cards, some of said cards having three types of indicia thereon, others having four types of indicia thereon and others having five types of indicia thereon.

3. In a baseball card game, a plurality of cards having indicia thereon, by means of which baseball plays may be simulated, substantially all of the cards having indicia thereon to indicate the particular portion of field to which the safe hits are made.

4. A base ball card game comprising a deck of cards, each card having thereon indicia representing the three major phases of action of a base ball game comprising pitching and batting, base running and fielding.

5. A playing card deck comprising a plurality of cards having a center design of three types, indicating caught out stealing, safe in stealing, and caught out in returning after an attempted steal, each of the cards in the deck having one of these designs thereon.

6. A playing card deck comprising a plurality of cards having illustrations at the side of each card, indicating singles, doubles, triples, home runs, throw outs, fly outs to the outfield, and double plays, each card

having at least one of these illustrations thereon.

7. A playing card deck comprising a plurality of cards having a center design of three types, indicating caught out stealing, safe in stealing, caught out in returning after an attempted steal, each of the cards in the deck having one of these designs thereon, and designs representing a pitched ball on each card.

8. In a deck of playing cards, a plurality of cards each having thereon indications of one or more baseball plays in combination with a design to indicate in playing the game, which baseball play has been effected.

9. In a deck of playing cards, a plurality of cards each having thereon indications of one or more baseball plays in combination with a design to indicate in playing the game, which baseball play has been effected, and indicia to disclose when a play has been effected which player or players in the outfield or infield participated in the play.

10. In a baseball card game, a plurality of cards having indicia thereon whereby a baseball game may be simulated, each card having thereon indicia indicating pitched balls and each of these indicia having associated therewith indicia to indicate whether the ball pitched was either a straight fast ball, an incurve or an outcurve.

In testimony whereof I have hereunto set my hand on this 30 day of November A. D. 1925.

MAXIMILIAN C. MEYER.
